AIRPLANE PROPELLING MEANS

Albert L. Widdis, Harrisville, Mich.

Application August 4, 1937, Serial No. 157,283

12 Claims. (Cl. 170—172)

This invention relates to an airplane propelling means which includes a centrifugal device through which air is propelled at high velocities, the incoming air being baffled and struck obliquely prior to entering the centrifuge.

An object of my invention is to provide a novel centrifugal means, such as the blades of an airplane propeller, the blades being hollow, and the velocities of these blades will cause a high degree of vacuum to exist along the trailing edge of the blade, and also at its outer end. This vacuum caused by this centrifugal device will draw air rapidly from adjacent the center of revolution and move this air outwardly at high velocity. The air before entering the centrifugal device being caused to impinge upon one or more baffle plates having intake means, with beveled rear edges, thus causing a forward thrust or force, which will materially aid in propelling an airplane, or the like.

A further object of my invention is to provide a novel airplane propelling means which will require no additional power on the part of the driving engine, and which will materially add to the forward thrust caused by the centrifuge, i. e., of the propeller.

Other objects, advantages and features of invention, may appear from the accompanying drawing, the subjoined detailed description and the appended claims.

In the drawing—

Figure 1 is a fragmentary side elevation, partly in section, of an airplane propeller, illustrating my novel propelling means mounted thereon.

Figure 2 is a fragmentary face view of one of the baffle plates showing intake means having beveled oblique, rear edges.

Figure 3 is a fragmentary transverse sectional view of a modified form of centrifugal device.

Figure 4 is a sectional view taken on line 4—4 of Figure 3.

Figure 5 is a plan view partly in section of still another modified form of centrifuge.

Figure 6 is a sectional view taken on line 6—6 of Figure 5.

Referring more particularly to the drawing, the numeral 1 indicates a propeller, the shape of which is usual and well known and conforms to usual airplane practice. The propeller is driven by the motor shaft 2, upon which it is mounted.

A conduit or duct 3 extends outwardly through each of the blades of the propeller from adjacent the center thereof to the outer tips. The inner ends of these conduits extend rearwardly as shown at 4, and open into a ring 5, which revolves with the propeller. A plurality of transverse baffle plates 6 are mounted within the ring 5. These plates are foraminated so as to permit the movement of air through the ring, but this air is baffled and struck obliquely by the beveled rear

edges of the air intake means and thereafter impinges upon these plates under high velocity, to cause a forward thrust.

Air is taken in at approximately atmospheric pressure at the rear end and walls of the ring 5 and to control the amount of air entering, I provide a plate 7 which is longitudinally adjustable on the shaft 2, or about this shaft, this plate being solid and will upon adjustment allow the required amount of air to enter through the walls 10 and end the ring.

When the airplane propeller is revolving at high speeds, a high degree of vacuum is created at the tips, and consequently air will move rapidly through the ring 5, and thence outwardly through the conduits 3. This rapidly moving air (which enters at atmospheric pressure) is baffled and struck obliquely by the beveled rear edges of the air intake means, and thereafter impinges upon the baffle plates 6 to cause the material forward thrust, thereby aiding the propelling of the airplane.

In the modification disclosed in Figures 3 and 4, particularly applicable to a ship, or the like, a substantially conical housing 8 is provided, formed 25 with a diverging conduit 9, through which air is drawn from the central intake 10. The conduit 9 is divided into compartments by the ribs 11 and transverse baffles 12, providing means against which the air impinges. The housing 8 is driven 30 from a suitable source of power on the shaft 13.

In Figures 5 and 6, particularly applicable to a land vehicle such as an automobile, radial ribs 14 are arranged between the heads 15—16. The structure is rotated by shaft 17 from a suitable 35 source of power. A ring 18 similar in construction to the ring 5 is provided with a plurality of baffles 19, which are similar in construction to the baffles 6. Air is admitted to the space between the ribs 14 through openings 20, said openings extending through the head 16, and within the area enclosed by the ring 18.

A control plate 21 enables the operator to adjust the amount of air which is admitted to the ring 18. The rapid revolving of the ribs 14 will 45 cause the air to be moved outwardly under high velocity, and the operation is the same as described under Figure 1.

The modifications shown in Figures 3 to 6 inclusive can be arranged either horizontally or 50 vertically as desired, and may also be used singly, or in pairs, arranged in tandem.

Having described my invention, I claim:

1. An airplane propelling means comprising a centrifugal device, drive means for said centrifugal device, air intake means for the centrifugal device, through which atmospheric air passes and baffles means which strike obliquely the air flowing toward the centrifugal device from the rear and plates against which air impinges, said 55 60

baffle means and plates being arranged at the rear of the centrifugal device to impart a forward thrust to the airplane.

5 2. An airplane propelling means, comprising a centrifugal device, drive means for said centrifugal device, air intake means for the centrifugal device, through which atmospheric air passes, and baffle means which strike obliquely the air flowing toward the centrifugal device from the 10 rear, plates against which this air presses and adjustable air control means at the air intake, of such nature that the quantity of air entering the centrifugal device may be adjusted, said baffle means and plates being arranged at the rear 15 of the centrifugal device, to impart a forward thrust to the airplane.

20 3. An airplane propelling means comprising a centrifugal device, drive means for said centrifugal device extending from the motor of the airplane to the centrifugal device, an atmospheric air intake adjacent the center of revolution of the centrifugal device and baffle means which strike obliquely the air flowing toward the centrifugal device from the rear, plates against which 25 this air presses, said baffle means and plates being arranged at the rear of the centrifugal device to impart a forward thrust to the airplane.

30 4. An airplane propelling means, comprising an airplane propeller, said propeller having air ducts extending through the blades thereof and terminating at the tips of the blades, an air intake means adjacent the hub of the propeller through which atmospheric air is drawn, and baffle means which strike obliquely the air flowing toward the 35 centrifugal device from the rear, and plates against which this air impinges, said baffle means and plates being arranged at the rear of the centrifugal device to impart a forward thrust to the airplane.

40 5. An airplane propelling means comprising an airplane propeller, said propeller having air ducts extending through the blades thereof and terminating at the tips of the blades, atmospheric air intakes adjacent the hub of the propeller through the walls and end of a ring mounted on the propeller at the hub thereof, baffles in the ring which strike obliquely the air flowing toward the centrifugal device through the ring from the rear, and plates within the ring against which this air 45 impinges, said baffle means and plates being arranged at the rear of the centrifugal device to impart a forward thrust to the airplane.

50 6. An airplane propelling means comprising an airplane propeller, said propeller having air ducts extending through the blades thereof and terminating at the tips of the blades, atmospheric air intakes adjacent the hub of the propeller through the walls and end of a ring mounted on the propeller at the rear hub thereof, baffles which strike obliquely the air flowing toward the centrifugal 55 device from the rear and plates against which this air impinges, said baffles and plates being arranged at the rear of the centrifugal device to impart a forward thrust to the airplane.

60 7. A propelling means comprising a conical centrifugal device, said centrifugal device having a divergent conduit extending therethrough, atmospheric air intake means at the center and in front of the centrifugal device, and baffles in the conduit against which the air is thrown.

70 8. A propelling means comprising a centrifugal device including a plurality of radial vanes, a drive shaft on which the vanes are mounted, a

ring surrounding the shaft at the rear of the centrifugal device and rotating with the vanes, baffles in the ring which strike obliquely the air flowing toward the centrifugal device from the rear through the walls and end of said ring, 5 plates in said ring against which the air impinges, said centrifugal device having atmospheric air intake ports extending from the ring to the vanes.

9. A propelling means comprising a propeller adapted to be rotated, having hollow blades open 10 at their outer ends, with fluid intake means through the forward and rear walls of the blades, so that when rotated a partial vacuum is created within the blades, fluid in front of the blades will pass into the partial vacuum within them, creating a partial vacuum in front of the propeller into which the airplane will pass; and at the same time columns of fluid will pass into the partial vacuum in the blades through their rear walls, and the rearwardly aligned rear walls of the 15 blades will obliquely hit, strike and baffle the air advancing toward the centrifugal device from the rear, creating a thrust in the direction of the air flowing toward the partial vacuum from the rear.

10. A propelling means comprising a propeller adapted to be rotated with hollow blades, open 20 at their outer ends, their inner ends bent so that their outer ends project rearwardly, with fluid intake means through the forward and rear walls 25 of the blades, so that when rotated a partial vacuum is created within said blades, fluid in front of the blades passes into the partial vacuum within them, creating a partial vacuum in front of the propeller into which the airplane will pass, at the same time columns of fluid pass into the partial vacuum in the blades through the rear 30 fluid intake means, and the rearwardly aligned rear sides of the blades will obliquely hit, strike and baffle this fluid inflowing from the rear and thereby create a thrust in the direction of the 35 flow of fluid into or toward the partial vacuum, while the air discharged rearwardly through the open ends of the blades causes a forward thrust.

11. A propelling means comprising a centrifugal device, of spiral form, adapted to be rotated and to create a partial vacuum therein, fluid intake means in the forward and rear walls of the centrifugal device admitting fluid into the centrifugal device, so as to form a partial vacuum in front of the centrifugal device into which the airplane, automobile, or ship will pass and at the same time be thrust forward by the spiral 45 rear wall of the centrifugal device obliquely hitting, striking and baffling the flow of fluid advancing toward the partial vacuum in the 50 centrifugal device through the fluid intake means in the rear wall of the centrifugal device.

12. A propelling means comprising a centrifugal device, of spiral form, adapted to be rotated, 60 radial partitions projecting from the front and rear sides of the centrifugal device, whereby, when rotated, a partial vacuum will be created at the front and rear sides of the centrifugal device in the spaces between the radial partitions, and baffles extending from the rear edges of the 65 rear radial partitions which will strike obliquely the air advancing toward the partial vacuum at the rear of the centrifugal device, whereby a thrust will be imparted to the airplane in the direction of the flow toward the vacuum at the 70 rear of the centrifugal device.

ALBERT L. WIDDIS.
